CLAIM

The ornamental design for a tool handle, as shown and described.

DESCRIPTION

FIG. 1 is a perspective view of a tool handle showing the new design;

FIG. 2 is an elevational view of the right side of the tool handle of FIG. 1;

FIG. 3 is an elevational view of the left side of the tool handle of FIG. 1;

FIG. 4 is an elevational view of the rear side of the tool handle of FIG. 1;

FIG. 5 is an elevational view of the front side of the tool handle of FIG. 1;

FIG. 6 is a plan view of the top side of the tool handle of FIG. 1;

FIG. 7 is a plan view of the bottom side of the tool handle of FIG. 1;

FIG. 8 is a perspective view of second embodiment of a tool handle showing the new design;

FIG. 9 is an elevational view of the front side of the tool handle of FIG. 1;

FIG. 10 is an elevational view of the right side of the tool handle of FIG. 1;

FIG. 11 is an elevational view of the rear side of the tool handle of FIG. 1;

FIG. 12 is an elevational view of the left side of the tool handle of FIG. 1;

FIG. 13 is a plan view of the bottom side of the tool handle of FIG. 1; and,

FIG. 14 is a plan view of the top side of the tool handle of FIG. 1.

The broken lines shown in the drawings are for the purpose of illustrating unclaimed portions of the tool handle and form no part of the claimed design.
